(57) **CLAIM**

The ornamental design for a dual electric vehicle charging station, as shown and described.

DESCRIPTION

FIG. 1 shows a perspective view of a first embodiment of a dual electric vehicle charging station;

FIG. 2 shows a front view of the dual electric vehicle charging station of FIG. 1;

FIG. 3 shows a back view of the dual electric vehicle charging station of FIG. 1;

FIG. 4 shows a right view of the dual electric vehicle charging station of FIG. 1;

FIG. 5 shows a left view of the dual electric vehicle charging station of FIG. 1;

FIG. 6 shows a top view of the dual electric vehicle charging station of FIG. 1;

FIG. 7 shows a bottom view of the dual electric vehicle charging station of FIG. 1;

FIG. 8 shows a detailed view of the body of the dual electric vehicle charging station of FIG. 1;

FIG. 9 shows a perspective view of a second embodiment of a dual electric vehicle charging station;

FIG. 10 shows a front view of the dual electric vehicle charging station of FIG. 9;

FIG. 11 shows a back view of the dual electric vehicle charging station of FIG. 9;

FIG. 12 shows a right view of the dual electric vehicle charging station of FIG. 9;

FIG. 13 shows a left view of the dual electric vehicle charging station of FIG. 9;

FIG. 14 shows a top view of the dual electric vehicle charging station of FIG. 9;

FIG. 15 shows a bottom view of the dual electric vehicle charging station of FIG. 9; and,

FIG. 16 shows a detailed view of the body of the dual electric vehicle charging station of FIG. 9.

The broken lines illustrate environmental structure and form no part of the claimed design.
